SELF STORING STORM WINDOW

James D. Reinhardt, Louisville, Ky., assignor to Aluminum Home Products Corporation, Louisville, Ky., a corporation of Kentucky

Application September 13, 1954, Serial No. 455,634

7 Claims. (Cl. 160—90)

The present invention relates to self storing storm windows.

Storm windows of the self storing type generally comprise a frame which carries upper and lower glazed sash and a screen sash which may be inserted to replace the lower glazed sash. Provision is made for storing the third sash, whether screen or glazed, when not in use, usually in a position adjacent and parallel to the upper sash.

In multiple track storm windows, of which I am aware, the upper glazed, lower glazed and screened sashes move in parallel tracks, and when the screen sash is in the lower opening and it is desired to remove the screen sash, it is necessary to first remove the stored lower glazed sash, and then remove the upper glazed sash, in order to remove the screen. When the glazed sash is in the lower position and the screen is stored, it is necessary to remove the screen before the lower glazed sash can be removed. This makes it inconvenient to open the storm window. A further disadvantage of the multiple track storm window resides in its higher cost of manufacture as compared to the one track or trackless window.

It is an object of the present invention to provide a storm window in which the easy change over of the multi track storm window is embodied in a trackless one over one type of window, and in which the various sashes are more easily removed or opened. The one over one type window is the designation in the trade for the type in which the upper and lower glazed sashes are in alignment.

Another object of the invention is to provide a trackless storm window in which, when the screen sash is positioned in the lower opening of the frame, the glazed sash may be quickly and easily shifted from its storage position to a position closing the screened opening by a sliding movement, without having to remove the screen, and wherein the glazed lower sash is secured in such position.

Another object is the provision of a one over one storm window in which the upper glazed sash is removably held in position independently of the other sashes.

Another object is the provision of a storm window having a screen sash arranged to hold a glazed sash securely in parallel relation to close the screened opening.

In accordance with the present invention I provide a trackless storm window frame of the one over one type in which the upper glazed sash is releasably retained by the frame against dropping, and against moving inwardly, and in which the lower opening may receive the glazed sash or screen sash, as desired, in alignment with the upper glazed sash. When the screen sash is in the lower opening it is retained at the bottom by a flange depending into a groove in the bottom or sill of the window frame, and the top of the screen sash may be retained against inward movement by a spring or by a releasable interlock with the upper sash. In this position of the screen sash the lower glazed sash may be stored in the upper portion of the frame parallel to and covering

2

the upper sash, or it may be lowered by a sliding movement to the lower portion of the frame parallel to and covering the screened sash. The screened sash has an inwardly extending flange provided with an upwardly opening groove, and the lower edge of the lower glazed sash has a depending flange received in said groove, when the glazed lower sash is lowered. The lower sash thus is releasably held at its bottom by the screened sash, which in turn is held by the frame, and at its top it is retained by a spring or the like. It will be seen that in this latter position storing of the screened sash is not necessary. To make the seasonal change it is only necessary to move the lower glazed sash to its stored position by an upward sliding movement. When the glazed sash is in stored position, the screened sash is easily removed by raising its depending flange out of the groove of the frame and drawing the sash inwardly, there being a pocket in the head of the frame deep enough to allow the upper sash to lift enough for the flange of the lower sash to raise out of the groove in the sill.

If desired the screened sash may be removed from the lower opening, in which case, the lower glazed sash may be slid from its stored position to its operative position in alignment with the upper glazed sash. The screen then may be inserted into its stored position. In such arrangement the flange on the bottom of the lower glazed sash is received in the groove in the bottom of the frame, and the upper end of the lower glazed sash is retained by a spring or by releasable interlock with the bottom of the upper sash, or in any other manner desired. The glazed lower sash is easily removed by lifting the sash and pulling it inward. The screened sash may be stored in the upper position parallel to the upper sash if desired, and in such position it is preferred that the screened sash overlap the lower glazed sash.

The invention also comprises a novel detent for holding the upper sash in raised position, this detent comprising an opening in the outer retaining flange of the storm window frame jamb and a struck out depending tongue on the bottom of the sash adapted to enter and overlie the opening.

The invention will be described in greater detail in connection with the accompanying drawing illustrating a preferred embodiment of the invention by way of example, and wherein:

Figure 1 is an elevational view showing the front or inside left of a metal storm window frame, with parts broken out, for a window structure embodying my invention, the sashes being omitted;

Figure 2 is a similar view of the rear or outside right half of the storm window frame;

Figure 3 is a sectional view taken respectively on the lines III—III of Figure 1, the storm window sashes being shown in dot and dash outline;

Figure 4 is a plan view of a detail of the frame;

Figure 5 is a front elevational view on an enlarged scale of a spring clip bracket;

Figure 6 is a fragmentary sectional view of a spring;

Figure 7 is a cross sectional view showing the operation of inserting (or removing) the upper glazed sash;

Figure 8 shows the lower glazed sash closing the screened sash;

Figure 9 is a cross sectional view showing the screened sash in the lower opening and the lower glazed sash in the upper storage position;

Figure 10 is a cross sectional view showing the upper glazed sash in position, the screened sash in storage, and the lower sash being inserted;

Figure 11 is a view similar to Figure 9, with the screened sash and lower glazed sash interchanged;

Figure 12 is a section taken on line XII—XII of Figure 7 showing the upper sash secured against dropping;

Figure 13 is a section taken on line XIII—XIII of Figure 12; and

Figure 14 is a similar sectional view of the upper rail of the lower glazed sash.

Referring to the drawing, the storm window frame comprises left and right stiles or jambs 1, 1' which are of generally Z shape in cross section, and bottom and top rails 2, 2' respectively, the rails and stiles being secured together in any suitable manner, as by self tapping sheet metal screws or the like. Each stile comprises an outer inturned flange 4, a web 5, and a flange 6, and the storm window frame may be secured to the outer stop strip 7 of the conventional window frame, by screws or the like, passing through flange 6 into the frame.

The bottom rail or sill 2 of the storm window frame may be formed as an extruded section and as shown in Figure 10, comprises vertical walls 8, 9 joined by a stepped horizontal wall 10 from which extends a tongue 11 that provides an upward opening groove 12. A rib or bead 13 at the lower end of wall 8 provides a reinforcement to increase the rigidity of the wall 8. A sealing strip 14 is provided to seal the lower edge of the rail, and bent over tabs 15 at the ends hold the strip in position. The top rail or head is of similar construction and therefore will not be described in detail, but where necessary to refer to details of the top rail the part will be designated by a primed similar numeral. At the bottom the ends of the bottom rail (Fig. 2) abut webs 5 of the stiles 1, 1' with the flanges 4 overlapping the bottom rail, and the stiles and rail are secured together by self tapping screws. At the top (Fig. 4) the horizontal wall 10' is grooved at 16 near the ends and the bead 13' is cut away at the ends to receive the flanges 4, which are held against tongue 11' by self tapping screws. Near the middle of each stile is secured a spring clip bracket 17, which may be riveted to flange 6. The spring clip bracket provides tabs 17a, 17b and 17c between which the bowed leaf spring 18 is received, the spring being loosely retained by means of punched teats received in similar punched sockets in the tabs.

The upper glazed sash 21 is received between the webs 5 of the left and right stiles and is biased against flanges 4 by engagement by the upper end of spring 18. The flanges 4 are each cut to provide an edge at 22 and the upper adjacent part of flange 4 is cut and bent out to form a tab 23. The lower rail 24 (Figs. 7 and 12) of the upper sash has a depending flange 25 the ends of which are offset at 26 to receive the end 22 of flange 4. The sash 21 may be raised into upper rail 2' high enough to allow flange 25 to pass over edge 22, and then by lowering the sash slightly edge 22 is received in the offset 26 and engages the bottom of the window rail 24 to act as a stop. In other words, each offset end 26 of flange 25 is received in the kerf provided between the edge 22 and the tab 23 of the adjacent jamb flange 4. This holds the upper glazed sash against dropping or being pushed inwardly.

The screened sash 27 (Figs. 8 and 9) has a lower rail 28 from which depends a flange 29 on its interior side. The screened sash is inserted into the frame substantially as illustrated in Figure 10 in connection with the lower sash, until its upper rail engages the upper glazed sash, and if necessary, the upper sash may be lifted by such engagement to allow insertion of the screened sash into the frame. After being thus inserted the screened sash is pulled down slightly to cause its flange 29 to enter groove 12 and thereby retain the sash at the bottom against inward displacement from the frame. A flange 30 extending from the lower rail of the sash serves as a hand lift. The bottom rail 24 (Fig. 13) of the top sash may have struck out tongues 31 which fit into the external groove 32 around the screened sash, and this interlocking arrangement holds the screened sash from being pushed inward at the top. It will be noted that when the screened sash is in the lower opening, the lower glazed sash 33 is

in its upper stored position shown in Fig. 9 substantially parallel and covering the upper glazed sash 21. Although the upper leaf of the spring 18 pushing the two sashes 33 and 21 against flange 4 is enough to prevent the glazed sash from dropping, I prefer to provide struck out tabs 34 on the lower end of the spring to provide a more positive lock to hold the stored lower sash in position.

The lower glazed sash 33, as shown in Figures 8 and 9, has a depending flange 36 on its interior side and a horizontal flange 37 is provided to serve as a hand lift. The flange 36 of the screened sash is formed to provide an upwardly opening groove 38 in registry with the flange 36. To lower the lower glazed sash from its stored position, the spring 18 is drawn to the left (Fig. 9) to disengage the tab 34 from the bottom of the sash, and the lower glazed sash 33 is slid downwardly until its flange 36 nests in the groove or socket 38 of the screened sash. In this position the lower end of spring 18 holds the upper ends of glazed sash 33 and screen sash 27 against the flange 4, and at the bottom the screen sash is held in position by its flange 29 nesting into groove 12, while the lower glazed sash has its flange 36 nesting into groove 38.

If desired, the window may be left in the position shown in Figure 8 throughout the winter season as this provides a glazed upper and lower sash closing the openings of the frame. To convert the window from this condition to a screened window, it is necessary only to slide the lower glazed sash 33 upwardly to stored position where it is retained by spring 18 as shown in Figure 9, thus uncovering the screened sash. However, if it is not desired to have the screened sash in its lower position throughout the winter, the screened sash can be removed and placed in stored position as shown in Figures 10 and 11, and the lower sash 33 then inserted in the frame with its lower flange 36 received in the groove 12 of the lower rail of the frame. In this position the tab 31 in the upper sash extends into a socket 39 formed in the upper rail 41 of the lower sash so as to provide an interlock holding the upper end of the lower sash against displacement. However, if this interlock is omitted, the lower sash will still be held against displacement by the overlap of the screen sash, which in turn can move away from flange 4 only a short distance before it encounters the spring clip 17. In the position shown in Fig. 11 it is easy to remove the lower glazed sash, and this can be done without disturbing the stored screened sash 27 in any way. To remove the lower glazed sash 33 it is raised slightly until its flange 36 is lifted out of groove 12, and then the sash is drawn backwardly as illustrated in Figure 10 to remove it. The lower glazed sash may be restored to its position merely by inserting its upper end first into engagement with the upper sash 21, lifting sufficiently to enable the flange 36 to clear tongue 11, then pushing down the sash to cause its flange 36 to enter groove 12.

From the foregoing description it will be seen that the window structure embodies the following advantages:

- A. A lower construction cost by reason of the elimination of vertical tracks.
- B. Easy interchangeability of screened and glazed lower sash.
- C. For winter use, screen may be left in lower opening, in which case the window is converted to summer use merely by sliding upwardly the lower glazed sash.
- D. In summer position, screen is easily removed without having to remove lower sash.
- E. In winter condition with the screen stored in the upper portion the window can be opened without disturbing the screened sash.
- F. At all times all sashes are retained against removal from the exterior.

I claim as my invention:

1. A storm window comprising: a frame providing guides for receiving upper and lower sashes, said guides having outer retaining flanges, a kerf on each said flange

near the middle; and a depending flange on the upper sash having outwardly extending portions at its ends adapted to be received in said kerfs in overlapping relation to said retaining flanges.

2. A storm window comprising: an upper sash having a flange depending from the lower rail along the outside edge, the ends of said flange being offset outwardly; a lower sash having a flange depending from the lower rail; a frame having substantially planar jambs, each terminating in an inwardly directed stop flange at the outside edge, said frame providing an opening for receiving the upper and lower sashes in alignment; said frame at its top providing a channel to embrace the upper rail of the upper sash; each said stop flanges having a recess respectively about midway of the height thereof to receive the offset end of the upper sash flange to hold the upper sash in its upper position with said last mentioned flange on the exterior of said stop flanges; and said frame at its bottom having a channel to receive the flange depending from the lower sash to retain the lower sash in said frame.

3. A storm window as specified in claim 2 wherein: said lower sash has a lateral inwardly projecting portion at its bottom rail providing a groove; and a third sash has a flange depending from the lower rail thereof and adapted to be received in said latter mentioned groove.

4. A storm window comprising: a frame providing an opening for receiving upper and lower glazed sashes in vertical alignment therein; a screen sash; the lower glazed sash being movable to stored position in the frame inside the upper sash when the screen sash is in the lower opening; a depending flange on the lower edge of the lower glazed sash adjacent the interior edge thereof; a depending flange on the lower edge of the screen sash adjacent the interior edge thereof; said frame having in its sill member an upwardly open groove positioned to selectively receive either of said depending flanges of the screen sash or the glazed lower sash when either of said respective sashes are in said lower opening in alignment with said upper sash to retain said sashes against inward movement; and a horizontal flange at the lower end of the screen sash extending interiorly and having an upwardly open groove therein positioned so that, when the screen sash is in said lower opening in alignment with the upper sash and with the depending flange of the screen sash in said groove of said sill member, said groove in the horizontal flange receives the depending flange of the lower glazed

sash, to retain both screen and lower glazed sash against interior movement.

5. A storm window comprising: an upper sash, a lower sash having a flange depending from its lower edge; a frame having substantially planar interior jamb faces and a head and sill, said frame providing a trackless window opening and having an inwardly directed stop flange at the outside edge of each jamb, said window opening receiving said upper and lower sashes in vertical alignment; 10 the head of said frame providing a pocket for receiving the upper end of the upper sash to retain said upper end against inward movement; said sill having an upwardly open groove positioned to receive the depending flange of the lower sash when said lower sash is in the lower opening to restrain the lower end of said sash against inward movement; said pocket having sufficient height to permit raising of said lower sash to raise said upper sash into said pocket sufficiently to release the depending flange of the lower sash from said groove for removal of the lower sash from the frame by an inward movement; a screen sash; a depending flange on the lower edge of said screen sash; a horizontal flange on the lower end of said screen sash; said horizontal flange having an upwardly open groove therein; said groove in the sill being positioned 20 to alternately receive the depending flange of the lower sash or the screen sash; and said upwardly open groove in the horizontal flange being located so that, when the screen sash is in the window opening aligned with the upper sash, said groove in the horizontal flange receives 25 the depending flange of said lower sash.

6. The storm window of claim 5 including: spring clips biasing said sash against said stop flanges.

7. The storm window of claim 6 wherein: said spring clips include brackets attached to said jambs and overlying the window opening and a spring removably held in each bracket biasing the upper and lower sashes against said stop flanges.
